UNITED STATES PATENT OFFICE.

HARRY O. WOLFF, OF CHICAGO, ILLINOIS.

SUPPORT FOR CURTAINS AND DRAPERIES.

Application filed May 13, 1921. Serial No. 469,104.

To all whom it may concern:

Be it known that I, HARRY O. WOLFF, a citizen of the United States, residing at Chicago, county of Cook, and State of Illinois, 5 have invented certain new and useful Improvements in a Support for Curtains and Draperies, of which the following is a specification.

This invention relates to improvements in 10 supports for window curtains and draperies, and it consists in certain peculiarities of the construction, novel arrangement and combination of the various parts thereof as will be hereinafter more fully set forth and 15 specifically claimed.

The principal object of my present invention, is to provide means for supporting, at 20 windows, one or more curtains or drapes, which supporting means shall be simple and inexpensive in construction, strong, durable and efficient in operation, with its parts so made, arranged and co-operating with one another as to permit it to be easily mounted or placed in position on the window-casing 25 or wall, or to be readily removed therefrom.

Another object is to furnish a support of 30 the above named general character, which may include one or more longitudinally adjustable sectional rods or bars for the purpose of adapting them for use in connection with window casings of different widths, as well as, for easily inserting the sections 35 thereof in the loops or hems of the curtains or drapes, with which the same are generally provided at their upper ends for such purpose.

Still another object is to furnish a curtain or drape support of such construction and arrangement of its parts, that when mounted, or in operative position, they will interlock with one another in such a way as to prevent accidental dislocation, and besides, will occupy such positions as to present great resistance against vertical stress or 45 strain, thereby affording a strong and secure support for heavy drapery, if use of the same is desired.

Other objects and advantages of the invention will be obvious from the following 50 description and explanation.

In the accompanying drawings, which serve to illustrate an embodiment of the invention—

Fig. 1 is a plan view of a support constructed according to the invention, show-

ing the parts thereof broken for the convenience of illustration.

Fig. 2 is a plan view of a strip of metal 60 from which one of the supporting brackets of the device is made.

Fig. 3 is a detached perspective view of one of said supporting brackets.

Fig. 4 is a plan or face view of a blank piece of metal out of which one of the interlocking members or plates of the device 65 is made.

Fig. 5 is a detached perspective view of one of the interlocking members or plates.

Fig. 6 is a view partly in section and partly in elevation taken on line 6—6 of 70 Fig. 1 looking in the direction indicated by the arrows.

Fig. 7 is an enlarged sectional view taken on line 7—7 of Fig. 1, and

Fig. 8 is a perspective view of a fragment 75 of a modified form of one of the curtain-supporting tubes or rods.

Corresponding numerals of reference refer to like parts throughout the different 80 views of the drawings.

The numeral 10 designates a portion of an upright support such as a wall or window casing on which my improved support is shown as being mounted by means of a supporting bracket located near the upper end 85 of the window casing near each side thereof. These supporting brackets are practically counter-parts of one another, and by reversing them are made in right and left forms, or so that certain parts of one of the brackets will extend towards the other bracket 90 when said brackets are properly positioned on the window frame or casing.

As the brackets are substantially counter-parts of one another, a description of one 95 of them is deemed sufficient.

Referring now more particularly to Figs. 2 and 3 of the drawings, it will be seen that the supporting bracket, which is designated as a whole by the numeral 11 consists of an 100 elongated body 12 provided near each of its ends with an opening 13 for the reception of screws or the like used in securing the body 12 thereof on the wall or side of the window casing. The body 12 has extended 105 from one of its side edges an arm 14 and from its other side edge another arm 15, which latter arm is considerably longer than the arm 14. These arms are bent on the lines 16, see Fig. 2, so as to extend at right 110

angles yet in parallelism with one another from the face of the body 12, as will be readily understood by reference to Figs. 1 and 3 of the drawings. The free end portions of each of the arms 14 and 15 of the bracket are bent in the same direction on the transverse lines 17, see Fig. 2, thus furnishing each of the arms 14 and 15 with a laterally disposed flange 18, see Figs. 1, 3 and 7 10 of the drawings.

When the brackets 11 are mounted in their operative positions as shown in Fig. 1, it is obvious that the arms 14 and 15 of each bracket as well as the flanges 18 on said arms 15 will present their edges vertically, thus affording great strength or resistance against downward pressure or stress. It will also be observed in Figs. 1 and 3, that the arms 14 of the brackets 11 are located on the adjacent edges of the body 12 of said brackets while the arms 15 thereof are located at the opposed edges of said brackets. Furthermore, it will be observed that the arms 14 20 are much shorter than the arms 15, which 25 construction is for the purpose to be presently explained.

The rods or bars which support the curtains or drapes are by preference each made of two sections 19 and 20, which are adapted 30 to telescope with one another at their adjacent ends so as to be longitudinally adjustable to adapt them for use in connection with the arms of supporting brackets 11, when said brackets are disposed at greater 35 or less distance apart as may be required by window frames of different widths. The outer end of each of the sections of each supporting rod is formed with an elbow 21 the free end of each of which is extended at substantially a right angle to main portions of the sections 19 and 20 of the supporting rod or bar.

As will be clearly seen in Figs. 1, 6 and 7, and readily understood, each of the sections 45 19 and 20 of each of the supporting rods is formed of a cross-sectionally elongated piece of metal which, when the bar is in operative position presents its edges vertically. At each of its edges each of the sections 50 19 and 20 is provided with an inturned flange 22 which flanges by preference are co-extensive with said sections and are employed for the purpose of affording telescopic connections between the adjacent end 55 portions of the sections, for giving additional strength to the supporting bars or rods and for providing a socket at the outer end of each of the sections of each rod for the reception and retention of a member 23 60 which co-operate with the outer ends of the supporting rods and with the arms 14 and 15 and flanges 18 on said arms of the supporting brackets for interlocking engagement therewith. Each of the interlocking 65 members is designated as a whole by the nu-

meral 23 and is formed of a blank piece of metal substantially L-shaped or angular when viewed in plan as will be readily understood by reference to Fig. 4 of the drawings.

Each of the members 23 is provided at one of its ends by bending the strip of metal on the dotted lines 24, see Fig. 4, with an upturned flange or hook 25 to engage the lower edge of one of the arms 14 or 15 of one of the supporting brackets 11 as will be presently explained. The interlocking members 23, like the supporting brackets 11, are practically counterparts of one another except that they are made in rights and lefts, 70 that is to say, the members 23 employed at the left hand ends of the supporting rods have their flanges or hooks 25 extended upwardly along the sides of the members 23 adjacent the arms 14 and 15 of the supporting brackets with which arms they are adapted to engage, while the members 23 employed at the right hand ends of the supporting rods have their hooks or flanges 25 disposed along the surfaces of said members 75 adjacent the arms 14 and 15 of the supporting brackets with which arms they interlock.

By reference to Figs. 4 and 5, it will be seen and understood that the body of each of the members 23 is provided with a cut-away portion 26 in the edge of the longitudinally disposed arm 27 of said member adjacent the hook 25 on the other arm of said member. This cut-away portion or recess reduces the width of the arm 27 adjacent the hook 25 of the member 23 and thus enables the interlocking member 23 to be more readily placed in position on the arm of the supporting bracket therefor, and when positioned to be held in locked engagement therewith.

In positioning the members 23 carried by each of the supporting rods or bars, I have found it advantageous to present the ends of the bar and the members 23 which it carries, vertically above the arms, for instance, those indicated by the numeral 14 and on the adjacent sides thereof when by interposing the members 23 between the flanges 18 on said arms and the wall in 110 which operation the hooks 25 are disposed below the lower edges of the arms 14, and then by turning the bar outwardly from the wall the hooks 25 will be caused to engage the lower edges of the arms 14 and the 115 recesses in the arms 27 will be caused to receive and engage the upper edges of the flanges 18 and thus support the rod or bar in a horizontal position.

In order to more securely fasten the arms 125 27 of the interlocking members 23 in the sockets at the outer ends of each of the supporting bars, I form the arm 27 of each of the members 23 near the upper edge of said arm with a longitudinally extended rib 28 130

which is tortuous or serpentine in form. By this arrangement it is manifest that after a member 23 has been inserted in one of the end sockets of the supporting bar, the metal bar can be crimped against the rib 28 which will prevent the accidental withdrawal of said plate from its socket.

In Fig. 8 of the drawings, is shown a fragment of one of the sections of a modified form of the supporting bars for curtains or drapes which consists in employing tubular sections 29 which telescope with one another at their adjacent ends. In this modification, the outer end of each section 29 is provided with a vertically disposed flattened socket 30 having in the upper portion of its inner surface a longitudinally extended groove 31 to receive the tortuous and similarly extended rib 28 on one of the interlocking members 23, which member is inserted in the socketed portion 30 of the modified form of the supporting rod.

Having thus fully described my invention, what I claim as new and desire to secure by Letters Patent is—

In a device of the class described, the combination with a pair of suitably mounted and spaced supporting brackets, each con-

sisting of a securing body having extended from one of its faces at a right angle there- 30 to a pair of spaced arms of unequal length, each arm having at the extreme outer portion of the free end thereof and on corresponding sides and spaced from said body a lateral projection, the shorter arms of 35 said brackets being located adjacent one another, of an interlocking member consisting of a flat elongated body having a hook at one end of its lower edge to engage the lower edge of one of the arms of 40 said bracket between its lateral projection and said body, a sectional longitudinally adjustable supporting bar having its outer ends deflected in the same direction from the body of the bar and each provided with 45 a socket to receive the outer ends of the interlocking members on the longer arms of said brackets, and a sectional longitudinally adjustable supporting bar having its outer ends deflected in the same direction 50 from the body of the bar and each provided with a socket to receive the outer ends of the interlocking members on the shorter arms of said brackets, the deflected end portions of the bars being of equal length. 55

HARRY O. WOLFF.
